UNITED STATES PATENT OFFICE.

ATILIO REBORI, OF BUENOS AIRES, ARGENTINA.

TIME-CONTROLLED ACTUATING MECHANISM.

Application filed October 26, 1921. Serial No. 510,530.

To all whom it may concern:

Be it known that ATILIO REBORI, subject of the King of Italy, residing at Buenos Aires, Argentine Republic, has invented 5 certain new and useful Improvements in Time-Controlled Actuating Mechanism, of which the following is a specification.

This invention relates to improvements in time controlled mechanism for actuating a 10 switch or the like to regulate, for instance, the time of illuminating and extinguishing lamps.

The primary object of the invention is to furnish a novel automatic clock including mechanism which is daily advanced for a predetermined period of time and then daily retarded for another predetermined 15 period of time, so that the instant of illuminating or extinguishing lamps may be controlled with mathematical precision to accord with the sun's rising and setting. It is desirable in certain cases, to illuminate lamps at or about the time of sunset and to extinguish said lamps at or about sunrise. 20 As the time of the sun rising and setting varies during the year, it is necessary to provide mechanism to compensate for the variations in order that the control mechanism will operate properly during the year 25 for illuminating the lamps at or about sunset and to extinguish the same at or about sunrise.

Another object of the invention is to furnish three ordinary clock work mechanisms 30 so combined that the main one controls the speed of operation or regulates the other two, so that one of the auxiliary clock work mechanisms will be retarded during a portion of a year at the same time that the other 35 auxiliary clock work mechanism is accelerated and vice-versa.

A further object of the invention is to provide combined clock work mechanisms of the above mentioned type in which the 40 auxiliary clock work mechanisms control the movements of a prime mover which operates a switch actuating member or the like.

While the present invention was primarily 45 devised for the automatic illumination and extinguishment of lamps, it is obvious that the same type of mechanism may be employed in any instance where it is desired to control an actuating member, whose time

of actuation varies during a predetermined 55 period of time.

With the foregoing objects outlined, and with other objects in view which will appear as the description proceeds, the invention consists in the novel features herein- 60 after described in detail, illustrated in the accompanying drawings and more particularly pointed out in the appended claims.

Referring to the drawings:

Figure 1 is a diagrammatic front view 65 of the main clock work mechanism and the two auxiliary clock work mechanisms, together with the regulating means for the auxiliary clock work mechanisms which are controlled by the main clock work mechanism.

Fig. 2 is a diagrammatic rear view of the mechanism for actuating and controlling the switch operating member.

Fig. 3 is a detail plan view of the means 75 employed for regulating the auxiliary clock work mechanisms by the main clock work mechanism.

Fig. 4 is a plan view of a sinuousoidal disk which controls the auxiliary clock work 80 mechanism that regulates the time of extinguishment of the lamps.

Fig. 5 is a diagrammatic sectional view of the mechanism shown in Fig. 1.

Fig. 6 is a front view of the face of the 85 improved clock.

Fig. 7 is a diagrammatic view illustrating graphically the manner in which the regulating disks are plotted.

Fig. 8 is a detail diagrammatic view of a 90 portion of the mechanism which controls the operation of the switch actuating member. In this view the parts are shown in locked position.

Fig. 9 is a detail side view of a portion 95 of the controlling mechanism for the switch operating member.

Fig. 10 is a view similar to Fig. 8 but showing the parts in relatively different 100 positions.

Fig. 11 is a front view of locking mechanism forming part of the controlling means for the switch operating member.

Fig. 12 is a detail fragmentary view of certain parts of the switch operating mem- 105 ber controlling means.

Fig. 13 is a top plan view of the parts shown in Fig. 11.

Fig. 14 is a side view looking from the front of the clock of the switch operating member and the means which directly engages the same.

5 Fig. 15 is a top plan view of a rock shaft forming part of the switch operating member control means and showing the arms which are connected to said shaft.

10 Fig. 16 is a diagrammatic sectional view of the disks which are driven by the auxiliary clock work mechanisms and which control the operation of the switch operating member.

15 Fig. 17 is a front view of a detail.

Fig. 18 is a top plan view of a detail.

In the drawings and as illustrated particularly in Figures 1, 3, 4 and 5, A designates the central or main clock work mechanism; and B and C designate the auxiliary clock 20 work mechanisms.

25 The main clock work mechanism has a spring drum 1 which drives the gears 2, 3, 4 and 5 and the regulating means 6 and 8 for the main clock work mechanism. 7 designates the minute shaft.

30 The winding spring or drum 9 of the mechanism B drives the gears 10, 11, 12 and 13, and the latter actuates the regulating members 14 and 15.

35 17 designates the spring drum of the mechanism C, and this spring drum drives gears 18, 19, 20 and 21, the latter actuating the control or regulating means 22 and 23. The minute shaft of the mechanism B is numbered 16 and the minute shaft of the mechanism C is numbered 24.

40 The shaft of the spring drum 1 is provided with a gear 25 which actuates gears 26, 27, 28 and 29, and by this train of gearing the gear 29 is caused to make a complete revolution every 365 days.

45 The reference character 30 shown in Figure 1 designates the external outline of the sinuousoidal disks 35 and 40 which control the regulation of the auxiliary mechanisms B and C. The mechanism B has a fastening member 31 connected to its regulating spring 32, and this fastening member is fixed to a pivoted lever 33 provided at its lower end 50 with an adjustable screw 34 which bears against the periphery of the sinuousoidal disk 35. The clock work mechanism C is provided with a fastening member 36 connected to its regulator spring 37 and fixed to a depending arm or pivoted lever 38 which is provided at its lower end with an adjustable screw 39 that bears against the periphery of the sinuousoidal disk 40. The lever 33 is 55 pivotally mounted on the shaft 41 and is connected at its upper end 42 to one end of a spring 43, the other end of the spring being fastened to some fixed point in order to draw on the upper end of the pin 33 and cause its lower end to remain in contact with 60 the periphery of the disk 35. The lever 38

is pivotally mounted on the shaft 44, and its upper end 45 is connected to one end of a spring 46, the other end of the spring 46 being fastened to a fixed point, so that the screw 39 will be yieldingly held in engagement with the periphery of the disk 40.

70 The gear 29, which makes a complete revolution in 365 days, is provided with projecting bolts 47 on which the sinuousoidal disks 35 and 40 are mounted, so that the 75 disks also make a complete revolution every 365 days.

75 From the foregoing it will be seen that the primary portion of the improved mechanism includes the three sets of common clock work 80 mechanisms, A, B and C, which are preferably of the same size and type. In the operation of this new clock, the central mechanism A always operates at a normal rate, while mechanism B accelerates daily for a 85 period of almost six months, and during the remainder of the year retards, also daily, until it returns to the point of departure. During this time, mechanism C will, when mechanism B advances with reference to the 90 mechanism A, retard with reference both to mechanisms A and B, in such manner as to return to its point of departure in approximately the same time as the mechanism 95 B. Mechanisms B and C will always run in opposition to each other day by day. Owing to the provision of the sinuousoidal disks 35 and 40 the mechanisms B and C are regulated accurately to accomplish the result 100 sought. The circumference of each of the sinuousoidal disks varies almost continuously in its distance from the axis or center of the disk. These sinuousoidal disks perform inverse functions one to the other, one of them serves to advance progressively and daily 105 the time of a particular action (in the present case the illuminating or extinguishing of one or more lamps) during a certain period, keeping the interval more or less constant during a further period, and bringing 110 it back to its initial point during a third period, which completes a revolution of the disk. The other disk serves to bring about the extinguishing or lighting of the lights in inverse order to that in which they have 115 been lighted or extinguished, always in accordance with the hour which may be decided upon, based upon the hours of sunrise and sunset. These sinuousoidal disks are divided 120 into twelve equal portions corresponding to the twelve months of the year, and each fraction or month has its section or circumference ascending or descending with respect to the center, and to correspond to the month to which it has been assigned. In the present 125 instance these disks have been prepared to accord with the hours of sunrise and sunset at Buenos Aires. The disks are plotted in the following manner. From the daily variations in the hours of sunrise and sunset a 130

line is obtained, now ascending, now descending and again more or less constant, which, being traced around a circumference, produces for example on the disk controlling illumination, a line which at the end of December coincides with or touches the imaginary mean line or starting point, separates a little from this towards the center of January, separates still further and suddenly in February, accentuates its separation still more in March, diminishes a little in April and so on in a manner which is apparent from viewing Figures 3, 4 and 7.

When the sinusoidal line approaches the center, the clock work mechanism controlled by the same advances and the illumination is then produced before the "starting hour," and when it separates its distance from the center, the clock work mechanism controlled thereby retards and the illumination is produced later.

The operation of these disks is produced by mechanism A, so that they run normally and constantly at all times. These disks may both revolve in the same direction or otherwise. As a leap year occurs every four years, then provided the clock runs always correctly, the times of sunset and sunrise will show a difference of one day in relation to the clock, that is from one to three minutes, according to the sun. If the clock work mechanism A continues to run normally at a constant speed, then at the end of eight years the real difference would be only from two to five minutes. I mention these particulars to demonstrate that if my clock were not touched or regulated during a period of eight years the actual difference would be practically inappreciable.

The mechanism heretofore described may be utilized, as before stated, for controlling the time of the illuminating and extinguishing of lamps, and in order to accomplish this result, a switch operating member is primarily controlled by means actuated by the clock work mechanisms B and C. For the purpose of understanding this means, attention is directed to Figures 2, 8, 9, 10, 11, 12, 13, 14, 15, 16, 17 and 18. As best seen in Figure 2 the minute shaft 7 of the main clock work mechanism A is provided with a fixed gear or ratchet wheel 50, the teeth of which are unequal in number in order to accomplish a purpose herein-after explained. On account of the wheel 50 being fixed to the axle 7 it will be understood that this wheel makes a complete revolution every hour. As the ratchet wheel revolves, it engages the lever 52 and the arm 69 and pushes these parts away from the ratchet wheel. Owing to the teeth of the ratchet wheel being unequal in number it is pointed out that the ratchet wheel will not push the members 52 and 69 outwardly the full distance simultaneously. The lever

52 is fixed to a rock shaft 51, and this rock shaft carries fixed arms 53 and 54. When the parts are in the position shown in Figures 2 and 8, the arm 54 will engage a lug 55 projecting laterally from a gear wheel 56 and will prevent said gear wheel from rotating in one direction. This gear wheel 56 is driven by a gear 57 having a shaft 75 provided with a gear 76 driven by a gear 74, the latter is driven by a gear 73 actuated by a fourth spring drum 72 having a winding shaft 71. From this description it will be understood that when the drum 72 is wound, the gear 76 will have a tendency to constantly rotate, but the mechanism explained hereinafter will render this rotation intermittent. When the wheel 50 moves the arm 52 sufficiently far to rock the shaft 51 and cause movement of the arms 53 and 54, the arm 54 will release the lug 55 and the arm 53 will be withdrawn from one of the notches 58 in the wheel 70, and this permits the gear 56 to revolve until its lug 55 contacts with a lever 60. This lever as shown is of hook shape and normally projects into the path of movement of the lug 55, and said lever is fixed on a rock shaft 59 which carries a fixed arm 84, for a purpose hereinafter explained. In order for the lever 60 to permit the lug 55 to escape, it is necessary for the shaft 59 to revolve, and to permit this latter movement it is also necessary that the lever 64 descend, as said lever 64 is connected to the shaft 59 by means of connecting links 61. The connecting links 61 are fastened to the point 62, and the lever 64 oscillates about a pivot 63. The lever 64 is provided with a depending leg 65 which rests on the peripheries of disks 93 and 94 which are rotatable about the axis 7 and are diagrammatically shown in Figure 2 at the point 102. Each of the disks 93 and 94, as shown in Figures 9 and 12 are provided with peripheral notches 96, 97, and a peripheral recess 98, 99. The depending leg 65 has a foot at its lower end adapted to enter the notches 96, 97 and recesses 98, 99. The disks 93 and 94 are driven by means hereinafter explained from the auxiliary clock work mechanisms B and C, in order to bring the notches 96, 97 and recesses 98, 99 at the proper times into position to permit the entrance of the leg 65 into one of the notches and one of the recesses for the purpose of allowing the lever 64 to descend. It will therefore be seen that after the arm 54 has been rocked to release the lug 55, that the gear 56 will rotate until it is arrested by the lever 60. Then as soon as the leg 65 is permitted to enter one of notches 96, 97 and one of the recesses 98, 99, the lever 64 may descend and as it moves downwardly, the linkage 61 will, as shown in Fig. 2 turn the hook 60 in a clockwise direction, 130

so that said hook will release the lug 55 and permit the gear 56 to rotate in an anti-clockwise direction. As the gear 56 rotates, the gear 57 and notched wheel 70 will also 5 rotate. It is this movement of the wheel 70 which is utilized to actuate the member which controls the operation of the switch, and as best seen in Figs. 2 and 14, the switch actuating member consists of an arm 10 82 provided at one end with a sleeve 81 which is freely mounted on the shaft 59. The other end of the member 82 is provided 15 with a hook 83 adapted to be connected to the switch to be operated. The arm 82 at the times of its actuation, is struck by one of the pins 77 projecting laterally from the wheel 70. It will therefore be seen that when the wheel 70 is permitted to operate, the pins 77 will strike the member 82 and 20 cause actuation of the same.

It may sometimes occur that at the time that the lever or hook 60 is actuated to release the pin 55, that the arm 52 is at the outer end of one of the teeth of the ratchet 25 wheel 50 as shown in Fig. 10, and under such circumstances the wheels 56, 57 and 70 would continue to rotate and as the pins 77 would intermittently strike the arm 82, said arm would intermittently actuate the switch and 30 cause the same to first permit the illumination and then the extinguishment of the lamps. In order to prevent such an occurrence as this, the rock shaft 59 is provided with a fixed arm 84 which projects into the 35 path of movement of the pins 77, so each time a pin 77 engages the lever 84, said lever will rock the shaft 59 and this will cause the linkage 61 to raise the lever 64 and bring the hook or lever 60 into a position to 40 halt the rotation of the wheel 56. During such an occurrence, the lever 64 will move to a position above the upper end of a locking lever 66 and this locking lever will function for a certain time to hold the lever 64 45 elevated. The locking lever 66 is pivotally mounted at 68 and is connected to a spring 67 which yieldingly holds its fixed arm 69 in contact with the ratchet wheel 50.

If it should happen that the arm 69 is 50 engaged by the outer end of one of the teeth of the ratchet wheel 50, when the lever 64 is raised by the movement of the arm 84, the member 66 would of course be in a position where it would not lock the lever 64 in elevated position. Owing however, to the fact that the teeth on the ratchet wheel 50 are of unequal number, the free end of the arm 52 at such time will occupy a position in a depression between two of the teeth of the 55 ratchet wheel 50, and consequently the arm 54 will be in a position to engage the lug 55 and prevent continuous rotation of the member 56.

Fixed to the shaft 101 of the mechanism 60 C, is a pinion 85 which rotates the gears 86,

87 and the pinion 88 fixed to the tube 110, the latter in turn causes the rotation of the disk 94 which is the member that produces extinguishing action. Fixed to the shaft 100 of the mechanism B is the pinion 89 70 which drives the gears 90, 91 and the pinion 92 fixed to the tube 112. The latter rotates the disk 93 which controls the illumination. Both disks revolve with their respective pinions and the tubes 110 and 112, upon the 75 pivot tube 95 in which the shaft 7 rotates. Viewing these disks from the front (the back of the clock) they both revolve in an anti-clockwise direction, and with the same speed as their corresponding mechanisms B and C. 80 The illumination controlling disk 93 revolves faster than the extinguishment controlling disk 94 during the months from January to June, and slower during the months from July to December. 85

Referring to Figure 6, it will be seen that the face of the clock is composed of three dials, namely, the largest which indicates the exact hour of the day and corresponds to the mechanism A; the small dial 103 at the left 90 shows the hour corresponding to the position of the mechanism B, or that which indicates the hour of sunset for each day of the year, or the hour of illumination; and the dial 104 at the right is that which indicates the hour of sunrise for each day of the year, or the time of extinguishment. 95 Office 105 permits access to the minute hand shaft 7 of the mechanism A; 106 permits access to the axle 49 of the spring drum 1 of 100 the same mechanism; 107 and 108 permit access to the winding axles 100 and 101 of the side mechanisms B and C; 109 permits access to the shaft 71 for winding the spring 72 of the mechanism for lighting and extinguishing. The hours marked by the hands in the drawing are only for the sake of appearance. 105

From the foregoing, it is believed that the construction, operation and advantages 110 of the invention may readily be understood by those skilled in the art, and it is apparent that various changes may be made in the construction disclosed without departing from the spirit of the invention as expressed in the claims. 115

What I claim and desire to secure by Letters Patent is:

1. In combination, a main prime mover, controlling elements driven by said prime 120 mover, auxiliary prime movers having regulating means, means operatively connected with said controlling elements and said regulating means for causing the former to regulate the latter, a fourth prime mover, an operating member actuated by the fourth prime 125 mover, and regulating elements actuated by the auxiliary prime movers for controlling the operation of the fourth prime mover. 130

2. In combination, a main clock work mechanism, controlling elements actuated by said mechanism, auxiliary clock work mechanism having regulating means, means operatively connected with said regulating means and engageable with said controlling elements for causing the latter to control the former, a prime mover, an operating member actuated by the prime mover, and regulating elements actuated by the auxiliary clock work mechanisms for controlling the movements of said prime mover. 60
3. In combination, a main prime mover, controlling elements actuated by said prime mover, auxiliary prime movers having regulating means, means operatively connected with said regulating means and engageable with said controlling elements for controlling the former from the latter, an operating member, means for actuating said operating member, and means actuated by the auxiliary prime movers for controlling the movements of the last mentioned means. 70
4. A combination as claimed in claim 3 in which the main prime mover consists of clock work mechanism. 75
5. A combination as claimed in claim 3 in which each controlling element is provided with a cam surface. 80
6. A combination as claimed in claim 3 in which each controlling element consists of a disk having an annular cam surface. 90
7. A combination as claimed in claim 3 in which each controlling element consists of a sinusoidal disk. 95
8. A combination as claimed in claim 3 in which the means connected to the regulating means and engaging the controlling elements consists of pivoted levers provided with abutments engaging the controlling elements. 100
9. A combination as claimed in claim 3 in which the controlling elements consist of sinusoidal disks, and in which the means connected to the regulating means and engaging said controlling means consists of pivoted mounted levers provided with abutments engaging the peripheries of said sinusoidal disks. 105
10. A combination as claimed in claim 3 in which the means connected to said regulating means consists of levers pivotally mounted intermediate their ends, means for forcing said levers toward said controlling elements, and abutments mounted on said levers for engagement with said controlling elements. 110
11. A combination as claimed in claim 3 in which the auxiliary prime movers consist of clock work mechanism, and in which the regulating means for said auxiliary prime movers include springs. 115
12. A combination as claimed in claim 3 in which the means for actuating the operating member includes clock work mechanism. 65
13. A combination as claimed in claim 3 in which the main prime mover consists of clock work mechanism provided with a shaft, and a ratchet wheel fixed to said shaft, and in which the means for actuating the operating member includes clock work mechanism having means controlled by said ratchet wheel and said auxiliary prime movers. 70
14. In a mechanism of the class described, a plurality of prime movers, a disk driven by each of said prime movers and having a peripheral notch and recess, said disks being rotatable about a common axis, a pivotally mounted lever having a depending foot engageable with said notches and recesses to permit movement of said lever towards the axis of said disks, a clock work mechanism having a wheel provided with a projecting pin, a three-armed lever having one of its arms engageable with said pin for normally preventing movement of said clock working mechanism, a rock shaft operatively connected to the first mentioned lever and having a hook shaped lever normally projecting into the path of movement of said pin, said hook-shaped lever being adapted to move out of the path of movement of said pin when the first mentioned lever is depressed, a locking lever adapted to hold the first mentioned lever in raised position, time controlled mechanism for actuating the three-armed lever and said locking lever, and an operating member actuated by said clock work mechanism. 85
15. In combination, a main clock work mechanism, controlling elements driven thereby, auxiliary clock work mechanisms arranged on opposite sides of the main clock work mechanism, regulating means for the auxiliary clock work mechanisms, means operatively connected with said regulating means and engageable with said controlling elements for controlling the former from the latter, a switch actuating member, means for actuating said switch operating member, and means controlled by said auxiliary clock work mechanisms for controlling the last mentioned means. 110

In testimony whereof I have affixed my signature.

ATILIO REBORI.
